UNITED STATES PATENT OFFICE.

KNUT JONAS ELIAS HESSELMAN, OF STOCKHOLM, SWEDEN.

FUEL-PUMP FOR INTERNAL-COMBUSTION ENGINES.

1,078,438.

Specification of Letters Patent. Patented Nov. 11, 1913.

Application filed March 29, 1913. Serial No. 757,581.

To all whom it may concern:

Be it known that I, KNUT JONAS ELIAS HESSELMAN, a citizen of the Kingdom of Sweden, residing at Saltsjö - Storängen, Stockholm, Sweden, have invented new and useful Improvements in Fuel-Pumps for Internal-Combustion Engines, of which the following is a specification.

This invention relates to fuel pumps for internal combustion engines which are started and reversed by means of a gaseous agent under pressure, such as compressed air. In such internal combustion engines it is as well known necessary in the reversal to prevent the fuel pump or pumps from delivering fuel to the engine until the latter, after the controlling members thereof have been adjusted for the new direction of movement, has changed its direction of rotation.

The object of the present invention is to provide simple and reliable means which will cause the fuel pump to cease automatically to deliver fuel as soon as the controlling members of the engine are adjusted for reversal and to commence to deliver fuel as soon as the engine has changed its direction of rotation.

The invention consists in the combinations and arrangements of parts hereinafter set forth and pointed out in the claims.

In the accompanying drawing I have shown one embodiment of my invention.

Figure 1 shows a sectional view of a fuel pump and a driving device for the same. Fig. 2 shows a section on line A—B of Fig. 1.

Referring to the drawing, 1 indicates a fuel pump of well known construction the plunger 2 of which is connected with an arm 3 of a ring 4 on an eccentric 5 which may be made integral with or rigidly secured to a sleeve 6 or the like which is rotatably mounted on the crank shaft of the engine or on an arbitrary shaft 7 adapted to be driven by the engine. In said sleeve 6 are pivotally mounted two pawls 8 and 9 which are actuated by springs 10 and 11 respectively, tending to keep the pawls in engagement with corresponding tooth-like notches in the shaft 7. On the latter is further mounted a longitudinally slidable sleeve 12 surrounding the one end of the sleeve 6. The sleeve 12 may be displaced axially for instance by means of a hand lever 13, connected with reversing mechanism adapted to be connected to the controlling members for the valves,

cams and the like which should be adjusted when the engine is to be reversed. The sleeve 12 is inside formed with an annular groove 14 which when it is in position opposite either of the pawls 8, 9 allows the spring thereof to bring the pawl into engagement with the shaft while the other portions of the sleeve 12 prevent such an engagement.

The working of the device described is as follows: If the sleeve 12 is in the position shown in Fig. 1 and the shaft 7 rotates in the direction of the arrow in Fig. 2, the shaft 7 turns the sleeve 6 by means of the pawl 8, the sleeve 6 in its order driving the fuel pump by means of the eccentric 5. When the engine is to be reversed and the controlling members thereof for this purpose are adjusted for the new direction of rotation by means of the lever 13, the sleeve 12 is displaced longitudinally so that its groove 14 comes in position opposite the pawl 9, the latter being thereby released while the pawl 8 is brought out of engagement with the shaft 7. As long as the shaft 7 continues to rotate in the direction of the arrow in Fig. 2 it cannot turn the sleeve 6 in spite of the pawl 9 being in operative position in as much as said pawl slips on the shaft. The fuel pump thus does not deliver any fuel. As soon as the engine and thus also the shaft 7 change their direction of rotation, the shaft 7 turns the sleeve 6 by means of the pawl 9 so that the fuel pump again is put in operation.

It will be easily understood by those skilled in the art that for the pawls 8, 9 and the corresponding notches in the shaft 7 may be substituted any other arbitrary clutching devices each of which acts in one direction of rotation of the shaft serving to impart movement to the fuel pump.

Having now described my invention, what I claim as new and desire to secure by Letters Patent is:

1. The combination with a fuel pump for internal combustion engines of the kind set forth, of a driving shaft, means for transmitting motion to the fuel pump, two clutching devices serving to connect said driving shaft and said means for imparting motion to the fuel pump, each of said clutching devices being capable to act only in one direction of rotation of said shaft, and means for putting either of said clutching devices

into and at the same time the other out of operative position, substantially as and for the purpose set forth.

2. The combination with a fuel pump for internal combustion engines of the kind set forth, of a driving shaft formed with two tooth-like notches, a sleeve rotatably mounted on the said shaft, means for imparting motion from said sleeve to the fuel pump, two pawls pivotally mounted in said sleeve and each adapted to engage one of said notches, and means for putting either of said pawls into and at the same time the other out of operative position, substantially as and for the purpose set forth.

3. The combination with a fuel pump for internal combustion engines of the kind set forth, of a driving shaft formed with two tooth-like notches, a sleeve rotatably mounted

ed on the said shaft and formed with an eccentric portion, a ring loosely mounted on said eccentric portion and having an arm connected to the fuel pump, two spring actuated pawls pivotally mounted in said sleeve and each adapted to engage one of said notches, a second sleeve capable of being displaced longitudinally and formed with an annular groove, and means for displacing said second sleeve longitudinally, substantially as and for the purpose set forth.

In testimony that I claim the foregoing as my invention, I have signed my name in presence of two subscribing witnesses.

KNUT JONAS ELIAS HESSELMAN.
